DRESS SHIELD

Abraham N. Spánel, Rochester, N. Y.

Original application February 12, 1936, Serial No. 63,547. Divided and this application October 16, 1936, Serial No. 105,907

3 Claims. (Cl. 2-53)

This invention relates to dress shields, and is a division of applicant's copending application Serial No. 63,547, filed February 12, 1936.

The main feature of the present invention relates to the provision of a dress shield which protects garments against perspiration, which is durable and which is inexpensive to manufacture.

Another feature of the invention relates to novel latex foundations utilized in making dress shields.

The various features and advantages of the invention will appear from the detailed description and claims when taken with the drawing, in which Fig. 1 is a front elevation of a complete dress shield; Fig. 1a is a fragmentary front view of a modified type of dress shield; Fig. 1c is a front view of a further modified type of dress shield; Fig. 2 is a vertical section through the shield of Fig. 1; Figs. 2a and 2b are sectional fragments of shields having foundations with modified types of reinforced edges taken substantially on the line 2-2 of Fig. 1; Fig. 2c is a vertical section of the shield of Fig. 1c, the section being taken on the line 2c-2c of that figure; Fig. 3 is a front elevation of the latex foundation of the shields of Figs. 1 and 1a; and Fig. 4 is a vertical section through the foundation taken substantially on the line 4-4 of Fig. 3.

The shield 5, which is generally saddle-shaped, has the outline of a crescent, the upper edge 6 of the shield being concave to fit under the arm, and the flaps 7, 7 thereof being adapted to be fastened respectively in the sleeve and to the body of the garment at the sleeve opening. The shield includes a seamless latex foundation 8, preferably made by deposition from an aqueous dispersion of rubber. This foundation, which is made in the general shape of the shield, is concave or inwardly curved at its upper part 9 to conform to the under part of the arm and is provided with side flaps 10, 10. The edges of the flaps 10, 10 are reinforced by an integral ridge or accumulation of latex 11. As best illustrated in Fig. 4, this reinforcement is generally triangular in shape and terminates in a feather edge 12, although the reinforcement may be semi-pear-shaped in cross section as illustrated at 35 in Fig. 2a or may have the shape of a distorted ellipse as shown at 37 in Fig. 2b. The latex foundation adjacent the free edges of the side flaps is provided with a series of openings 13 by which a protective covering for the foundation can be sewed thereto without piercing the foundation. Each of the openings 13, which

may be circular or elongated holes, is reinforced by an integral ridge 14 generally triangular in cross section and terminating in a feather edge 15 (Fig. 4). It will be understood that where the edges of the foundation are reinforced as illustrated at 35 and 37 in Figs. 2a and 2b they may or may not be provided with openings 13 as desired.

The inner and outer surfaces of the foundation are respectively covered with saddle-shaped pieces of fabric 16 and 17 of the general shape and outline of the foundation. These pieces of fabric when assembled on the inner and outer surfaces of the foundation in the relation shown in Fig. 2, are fastened to the free edges 15 of the foundation flaps 10, 10 by stitches 18 which pass through the edges of the fabric pieces and through the reinforced holes 13 in the margin of the foundation. As illustrated in the fragmentary cross sectional views of Figs. 2a and 2b, the openings in the free margins of the flaps 10 have been omitted and the saddle-shaped pieces of the fabric 16 and 17 are attached to the free edges of the foundation, being stitched through the thickened reinforcements 35 and 37, or adjacent thereto.

In the modified type of shield shown in Fig. 1a, the outer and inner pieces of fabric 16 and 17 have been omitted so that in the finished shield a major portion of the latex foundation 30 is exposed. However, in this type of shield, wicking 19 or other similar absorbent material is overcast about each free edge of the flap, being threaded through the series of openings 13 in the margin of each flap. Instead of over-casting the absorbent material on the margin of the flaps, it can be threaded through the openings 13 in various ways. It will be understood that in this type of shield, the margin of the latex 35 at the openings 13 may or may not be reinforced as desired.

The further modified type of shield 5 illustrated in Figs. 1c and 2c, includes a crescent-shaped latex foundation having the connected side flaps 10. This foundation is partially covered by a strip of fabric 19 woven into saddle-shaped form so that its medial fold conforms to the curvature of the concave margin of the foundation. The fabric, woven in this shape, is 45 preferably obtained in rolls and can be cut to the necessary lengths to fit the shields. The cut ends of each piece of strip, are preferably overcast to prevent raveling. The strip is then suitably fastened to foundation in the position in- 50 55

dicated such as by stitching through the holes 13 and 13a in the foundation.

The present disclosure is given merely by way of example and it will be understood that there can be many modifications and variations therein within the scope of the appended claims without departing from the spirit of the present invention.

What I claim is:

- 10 1. A dress shield including a seamless, deposited latex foundation comprising two crescent-shaped flaps integrally curving into each other at the concave margins thereof, substantial portions of the convex margins of said flaps being strengthened by ridges of deposited latex integral therewith, absorbent material, and means for attaching said absorbent material to said foundation, said means comprising stitching passing through said ridges.
- 15 2. A dress shield including a seamless, deposited latex foundation comprising two crescent-
- 20

shaped flaps integrally curving into each other at the concave margins thereof, substantial portions of the convex margins of said flaps being strengthened by deposited ridges of latex integral therewith, absorbent material, and means for attaching said absorbent material to said foundation, said means comprising stitching passing through said strengthened convex margins of said flaps.

3. A dress shield including a seamless, deposited latex foundation comprising two crescent-shaped flaps integrally curving into each other at the concave margins thereof, substantial portions of the convex margins of said flaps being strengthened by deposited ridges of latex integral therewith, absorbent material, and means for attaching said absorbent material to said foundation, said means comprising stitching passing through said convex margins of said flaps adjacent said ridges of deposited latex.

ABRAHAM N. SPANEL.
